UNITED STATES PATENT OFFICE.

HARRY D. NEFF, OF CAMBRIDGE, MASSACHUSETTS, ASSIGNOR TO RE-FILIT BROOM COMPANY, OF BOSTON, MASSACHUSETTS, A CORPORATION OF MASSACHUSETTS.

MACHINE FOR MAKING BROOM BUNDLES OR UNITS.

Application filed May 14, 1921. Serial No. 469,736.

To all whom it may concern:

Be it known that I, HARRY D. NEFF, a citizen of the United States, and resident of Cambridge, in the county of Middlesex 5 and State of Massachusetts, have invented an Improvement in Machines for Making Broom Bundles or Units, of which the following description, in connection with the accompanying drawings, is a specification, 10 like letters on the drawings representing like parts.

My present invention relates to brooms or brushes, and more particularly to machines for making broom or brush bundles or 15 units.

In my Patent No. 1,367,753, dated Feb. 5, 1921, I have described and claimed an improved form of broom or brush in which a plurality of units or bundles of fibre are 20 arranged in a holder, and in my Patent No. 1,411,221, dated March 28, 1922, I have described and claimed the novel features of a unit or bundle adapted to be used in the holder of said first named application, 25 while in my Patent No. 1,421,812, dated July 4, 1922, I have described and claimed the novel features of the construction and arrangement of parts of a machine used in the manufacture of broom units or bundles 30 and particularly for completing the operation of placing the binding band in position thereon. The machine forming the subject matter of my present invention may be used in conjunction with the machine last 35 referred to, and its function is to partially complete broom or brush units by positioning binding bands thereon, such binding bands being deformed by the machine to an extent sufficient to enable them to maintain 40 their position on the broom or brush unit. In this partially completed condition the brush or broom bundles are fed to the machine above referred to, where the binding band is pressed into the proper size and 45 shape.

The principal object of my invention therefore, is an improved broom or brush unit or bundle making machine.

Another object is an improved device for 50 crimping the binding band of a broom or brush unit or bundle.

Other objects and novel features of the construction and arrangement of parts con-

stituting the machine will appear as the 55 description of the invention progresses.

In the accompanying drawings illustrating the preferred embodiments of my invention,

Fig. 1 is a side elevation,

Fig. 2 is a sectional plan view on the 60 line 2—2 of Fig. 1,

Fig. 3 is an end elevation with the sliding block removed,

Fig. 4 is a plan view of a modification,

Fig. 5 is a view of a band before crimping,

Fig. 6 is a view of the band after crimping, and

Fig. 7 is a perspective view of a unit or 70 bundle as made by the machine.

Referring to the drawings, 10 designates a base on which is secured, in any suitable manner, a rectangular block 11, provided with a recess 12, a counterbored portion 13, and a perforation 14, all lying in the same 75 axis. The diameter of the counterbored portion 13 is slightly greater than the external diameter of a band 15 adapted to be crimped, as at 16, to encircle and grip a unit or bundle 17 of fibres, such as broom 80 corn, bristles or the like, while the diameter of the perforation 14 is less than the diameter of the portion 13 and equal in diameter to the smallest diameter of the funnel shaped opening 18 in a block 19, this 85 block 19, either solid or split into two sections, as shown in the drawings, being an easy sliding fit in the recess 12. Longitudinal slots 20 diametrically arranged in the block 11 with respect to the counterbored 90 portion 13, each communicate, by means of a hole 21, with a hole 22 in which is slidably mounted a round ended plug 23, a coil spring 24, between the inner end of the plug 23 and the bottom of the hole 22 tending to force the plug 23 outwardly, 95 as clearly shown in Fig. 2. Attached to the plug 23, by a member 25, is a crimping tool 26, which is slidably mounted in the longitudinal slot 20. Pivotedly mounted 100 in the members 32 on the block 11 by screws 27 is a lever 28 provided with a handle 29, each leg of the lever being provided with a round headed bolt 30, secured to the lever by a nut 31, the rounded end of said bolts engaging with the round

ended plugs 23 to force the crimping tools 26 inwardly into the counterbored portion 13, as shown in Fig. 2. A plate 37, attached to the back of the block 11 by bolts 33, acts as a stop for material placed in the machine.

To operate the machine, the lever 28 is moved to the left, as shown in Fig. 1, to move the bolts 30 out of engagement with the round ended plugs 23, when the springs 24 move the crimping tools 26 out of the counterbored portions 13. The block 19 is removed from the recess 12, one of the bands 15 inserted in the counterbored portion 13, and the block 19 replaced in the recess. Enough fibres, such as broom corn, or the like, to form a unit or bundle 17 is forced into the funnel shaped opening 18, through the band 15 and the perforation 14 against the plate 37. The lever 28 is swung to the right, as viewed in Fig. 2, when the bolts 30 engage with the round ended plugs 23 to force the crimping tools 26 into the counterbored portion 13 to form the crimps 16 in the band 15, as shown in Fig. 3, in this manner causing the band 15 to engage the fibres and form a broom or brush unit or bundle.

Referring to Fig. 4, showing a modification of my invention, 10 designates the base having a block 34 mounted thereon in which is located a counterbored portion 13, a perforation 14, and all elements above described as being associated with the block 11, being in like manner associated with the block 34, except that in the present modification there is no sliding block 19. In place thereof I pivotally mount, on vertical axes on either side of the front of the block 34, two blocks 35 and 36, in each of which is formed one half of a funnel shaped orifice, the small diameter of this orifice being equal to the diameter of the perforation 14. The only difference in the operation of this modification over that of the forms described above, is that the blocks 35 and 36 are swung on their pivots into the dotted position shown in Fig. 4, to expose the counterbored por-

tion 13 for the insertion of the bands 15.

While I have described the preferred embodiments of my invention somewhat in detail, it is to be understood that I may vary the size, shape and arrangement of parts constituting my improved machine within wide limits without departing from the spirit of the invention.

Having thus described my invention, what I claim as new is:

1. In a machine of the class described, the combination of a body member provided with a band holding chamber, a removable block located in the body member in front of said chamber and having a funnel shaped orifice communicating with said chamber, and crimping means movable laterally with respect to said chamber.

2. In a machine of the class described, the combination of crimping means, a body member provided with a perforation and a band holding chamber, a block slidably mounted in said body means and provided with a funnel shaped orifice, the perforation, band holding chamber and funnel shaped orifice being in alinement with each other and constituting a positioning means for fibrous material, and means for moving the crimping means laterally with respect to said band holding chamber to crimp a band on a bundle of fibres.

3. In a machine of the class described, the combination of body means provided with a perforation and a band holding chamber, a block slidably mounted in said body means and provided with a funnel shaped opening, the perforation, band holding chamber and funnel shaped orifice being in alinement with each other and constituting a positioning means for fibrous material, and crimping means extending longitudinally of and movable laterally with respect to said band holding chamber to crimp a band on a bundle of fibre.

In testimony whereof I have signed my name to this specification.

HARRY D. NEFF.
